United States Patent Office.

WILLIAM HILL, OF POTTSVILLE, PENNSYLVANIA.

Letters Patent No. 93,085, dated July 27, 1869.

IMPROVEMENT IN METALLIC KEGS.

The Schedule referred to in these Letters Patent and making part of the same.

To all whom it may concern:

Be it known that I, WILLIAM HILL, of Pottsville, in the county of Schuylkill, and State of Pennsylvania, have invented a new and useful Improvement in Metallic Kegs; and I do hereby declare that the following is a full, clear, and exact description thereof, which will enable others skilled in the art to make and use the same, reference being had to the accompanying drawing, forming part of this specification.

His invention relates to a new and useful improvement in the manner of putting in the heads of kegs for containing powder and other articles when the same are made of metal, and consists in the peculiar form of joint made, and the bearings obtained for securing the contents and making the keg strong and durable.

In the accompanying drawing—

Figure 1 represents a keg complete, formed according to my invention.

Figure 2 is a top view.

Figure 3 is a detailed view, showing the form of joint, and the locks and bearings obtained.

Similar letters of reference indicate corresponding parts.

A is the cylinder which is made of iron or other suitable metal, having its upper edge bent inward to form a continuous hook or catch, as shown at a, fig. 3.

Near the upper edge the metal is pressed inward to form an exterior recess, b, and a corresponding interior shoulder, b'.

B is the head, having its edges bent upward, as shown, in such a manner that the part c shall catch under the hook a of the cylinder, while its shoulder d, rests firmly upon the shoulder b'.

The joint is perfected by pressing the portions a c together between suitable rollers or mandrels. By this construction the joints are made tight and the keg strong and durable, in the most perfect and expeditious manner.

It will be observed that the edge of the catch a rests also upon the shoulder f of the head, so that any undue pressure upon the top of the keg serves to force the shoulders f b' together, and against the shoulders c d of the head, thereby firmly clamping the latter in position. If desired, both heads of the keg may be riveted to the body in the same manner.

Access to the can is obtained through an orifice in the top which is covered by the grooved slide E.

Having thus described my invention,

What I claim as new, and desire to secure by Letters Patent, is—

Uniting the heads B to the body of the powder-keg by means of the joints and bearings a, b', c, d, and f, as herein shown and described.

WILLIAM HILL.
